CEMENT GUN NOZZLE

John T. Vawter, Los Angeles, Calif.

Application January 2, 1930. Serial No. 417,950

3 Claims. (Cl. 91—45)

This invention relates to cement gun nozzles and deals with the deposition of particles of a hydrated concrete mixture upon a surface by the usual air pressure means. The phenomenon of rebound is well known to the cement gun industry as a gradation or a series of degrees of rebound ranging between necessity at one end and a wholly unnecessary waste of material at the opposite end. In cases where extreme density of deposition is the chief aim, the rebound is accepted as the means by which the energy of the compressed air is transmitted to the surface to be condensed. But in cases where the density required is comparable to average hand work, rebound becomes an expensive nuisance both with respect to loss of time and material. This invention, therefore, broadly speaking, deals with the control of the amount and kind of rebound which occurs when a cementitious mixture is deposited by means of cement gun equipment.

In considering rebound, it is appreciated that two factors are involved. The first factor relates to the nature of the surface on which the deposit is made to take place, and the second deals with the ballistic properties of the particles of conveyed material. The characteristics of the depositing surface bear only an indirect relation to the problem involved in this invention and, consequently, will not be discussed since the present invention is more concerned with rebound due to causes more intimately connected with the momentum of air used in the transporting of the material and with the incident impact of the particles of material upon the depositing surface.

Rebound, in the sense as used in this invention, is intended to include the particles deflected from a depositing surface by the force of incident velocity and also those particles swept from the surface by the blast of released air which is shot directly against the surface with the material particles. This latter phenomenon may be termed "air erosion" and is one of the problems sought to be benefited by this invention.

Another aspect of this invention deals with the ballistics of the particles involved.

As to the ballistics of the particles of material, it is well understood that the incident velocity of the projected particles is derived from air propulsion. However, as soon as the air has conveyed each particle to the nozzle and has imparted a projecting velocity to the particles, the work of the air is finished and it then becomes a hindrance instead of a benefit in the further work of depositing. The ideal arrangement would be a nozzle wherein a complete separation of air

from the particles was effected prior to the particles leaving the nozzle. Under this arrangement, the particles would proceed on their own path of projection and would travel the remaining distance from the orifice of the nozzle to the surface of deposition under their own momentum. A nozzle designed upon this principle is fully described in my copending application, Serial No. 417,648, filed Dec. 31, 1929, and operates upon the principle of a tromb shaped nozzle whereby the air is deflected from the sand at substantially right angles to the flow of the sand as it leaves the nozzle orifice. It is thus obvious that by separating the air from the material, the disadvantage of sweeping particles, already deposited, from the depositing surface would be avoided. However, there remains another method of reducing rebound and the sweeping action of the air or what I term "air erosion" and that is by reducing the velocity of the air before it leaves the nozzle orifice. Means for this purpose is to be considered as one of the prime objects sought in this invention.

For the purpose of reducing air erosion, this invention contemplates a partial absorption of the air velocity at a point prior to the departure of the particles from the nozzle orifice. The principle involved in this invention is based upon the theory that the compressed air which is forcing the particles along the path of travel will have performed all of its useful work as soon as the nozzle orifice is reached and that unless it is deflected or its energy absorbed, it will continue to travel to the depositing surface and will impart its remaining energy to removing particles from the surface. In addition to removing particles it will set up eddy currents or counter currents in direct opposition to the depositing of material. In order to obviate this condition, I have devised a nozzle whereby the excess velocity of the air within the nozzle is applied to drawing outside air into the nozzle in a manner to partially absorb the unexpended energy remaining in the air. By this method the energy still remaining in the live air after it has delivered the particles to the nozzle orifice, is partially absorbed by setting into motion a volume of static air surrounding the exterior of the nozzle. The direct result is a decrease in the velocity of the sand and air column before leaving the nozzle orifice. This in turn reduces rebound of particles by decreasing the incident velocity and also tends to decrease air erosion by debilitating the air. A nozzle having the foregoing characteristics will be appreciated as accomplishing the major pur-

poses of this invention, namely, to decrease the rebound of particles by reducing the incident velocity thereof and to decrease air erosion of deposited particles by reducing the air velocity before it leaves the nozzle.

5 An added advantage resides in this arrangement for this reason. It is assumed that the density of deposited product depends largely upon the nozzle pressure. This assumption is based upon practice, and also upon the fact that various 10 city and country specifications for "Gunite" stipulate a minimum nozzle pressure in order to insure a certain density of product. Therefore, by 15 reason of work performed in the nozzle provided by this invention, it is clear that a considerable 20 resistance is offered to the passage of air therethrough and that, consequently, such a nozzle will maintain a comparatively high nozzle pressure which conforms to the above requirements in practice.

It is apparent that a combination of the principle of the present invention may be made with the principle of another of my inventions disclosed and claimed in my copending application, 25 Serial No. 417,647, filed Dec. 30, 1929. In the said copending application, the velocity of the particles is reduced by mechanical obstructing means. Evidently, a combination of the two principles, to wit: the present invention, and the foregoing 30 copending invention, would produce a nozzle particularly suitable for depositing cement in quarters where air erosion is objectionable and where high density of product is not required.

In my said copending application, Serial No. 417,648, filed Dec. 31, 1929, I have disclosed a 35 nozzle involving the tromb shaped nozzle. This arrangement, in combination with the principles of the present invention, produces a nozzle that greatly reduces the velocity of the released air and deflects the air emitted from the nozzle away 40 from the surface of deposition. This type of nozzle becomes extremely useful where air erosion is sought to be eliminated and where comparatively high density and a large volume of material 45 is of prime importance.

Other objects and advantages will become apparent upon a reading of the description taken in conjunction with the drawing in which

Fig. 1 is a side elevation partly in section illustrating the principle of my invention;

Fig. 2 is an end elevation taken on line 2-2 of Fig. 1;

Fig. 3 shows an embodiment involving the principle of this invention incorporated with an obstruction in the path of the projected sand particles to decrease the velocity of said particles; and

Fig. 4 shows another combination of principles in which the principle of this invention is incorporated with a second principle of deflecting the excess air from the path of the projected particles.

In the drawing herewith, I have more or less diagrammatically illustrated my invention and have shown a nozzle A attached to a water ring B which in turn is mounted upon a conventional material conveying hose C. In all the forms of nozzles embodied in this invention, there is incorporated an air passage or a series of air passages designated at 11. The passages 11 will be appreciated as providing communication from the exterior of the nozzle to the interior of said nozzle.

In the operation of the nozzle embodying the principle of absorbing the excess velocity of the

air transporting medium before it leaves the nozzle orifice, which form is illustrated in Fig. 1, the sand particles are conveyed through the hose C and are hydrated in passing through the water ring B whereupon they pass outwardly in a sand and air column in the direction of the arrow 12. As the particles propelled by the air continue to pass outwardly through the nozzle A, the air passages 11 begin to operate and serve to communicate the zone of static air surrounding the exterior of the nozzle with the interior of the nozzle. This arrangement is recognized as providing an aspirating means of drawing outer air through the passages 11 into the interior of the nozzle A by means of the excess energy of the air which has transported the material to this point and has no further usefulness. It is readily understood that by thus setting up a movement to a volume of external air, a large percentage of the energy of the live air within the nozzle is absorbed. This principle of partially absorbing the velocity of live air within the nozzle after it has performed its usefulness by causing it to move a volume of dead air, is to be considered as the basis of my invention, and operates to materially reduce the velocity of the sand and air column, the consequence of which is to decrease the speed of the particle before being projected. By thus decreasing the speed of the particles and the velocity of the air, the rebound of particles due to incident velocity and erosion of particles due to released air is reduced. A nozzle of this type operates satisfactorily to deposit a large volume of product having an average density. The chief benefit of such a nozzle is the reduction of rebound due to incident velocity and impact of the particles and a lessening of air erosion.

In Fig. 3, I have embodied the principles of the present invention with the principle of another of my inventions disclosed in said copending application, Serial No. 417,647. It will be noted in Fig. 3 that the same nozzle A is utilized in conjunction with a conventional water ring B and the usual material conveying hose C. The same air passages 11 are provided and the velocity of the excess air is absorbed in the same manner. However, in this arrangement, I have embodied an obstructing element D arranged in the path of the sand particles. The purpose of this arrangement is to cause a disturbance amongst the particles and thereby appreciably decrease the velocity of the particles themselves. This arrangement obviously increases the benefits sought to be effected by this invention, namely, the minimizing of rebound of particles by decreasing the velocity thereof and the reduction of air erosion by absorbing a certain amount of excess air velocity. A nozzle of this character is particularly adapted to reduce air erosion and to deposit a large volume of material where density of product is not of prime importance.

Fig. 4 illustrates the principle of the present invention in combination with the principle of another of my inventions. In the illustration shown in Fig. 4, I have incorporated adaptations of the tromb shaped type of nozzle designated 15 and 15'. In combination with the nozzle 15, I use the same air admitting passages 11. It is to be understood that the method of absorbing the velocity of excess air is identical with the method disclosed in the present invention. In combination with this arrangement, I have illustrated a second arrangement comprising an adaptation of a tromb designated 15' which is

arranged to deflect air separated from the column of sand and air by expansion through passages 16. This principle of deflecting air from the sand column has been fully described and 5 claimed in my copending application, Serial No. 417,648, filed Dec. 31, 1929.

In combining the principle of this invention with the principle of the above mentioned invention, an intermediate member 17 is incorporated between the tromb 15 and a tromb 15' and is shaped in a manner to define one side of the 10 passages 11 and 16. This type of nozzle may be said to meet the general requirements of the 15 elimination of air erosion and the reduction of particle speed. A nozzle of this character will find general usefulness in almost all kinds of work.

In the drawings shown, it is to be understood that the principles involved are more or 20 less diagrammatically shown and that this invention is intended to include all forms of nozzles which embody the principles disclosed in the drawing and the specification.

I claim as my invention:

25 1. In a nozzle for use with cement gun equip-

ment: means for reducing the speed of the particles projected therethrough, said means including passages in said nozzle arranged to communicate the flowing air within the nozzle with exterior air surrounding the nozzle; and a particle 80 obstructing element arranged within the orifice of the nozzle.

2. A nozzle of the character described comprising: a casing adapted to be mounted upon a material conveying conduit, said casing embodying an expanding nozzle having passages communicating the interior of said nozzle with the exterior air surrounding said nozzle; and a particle 85 obstructing element arranged in the orifice of said nozzle.

3. A nozzle of the character described comprising: a casing adapted to be mounted on the discharge end of a material conveying conduit, said casing forming an expanding nozzle having its inlet end spaced apart from the end of the conduit to form an air inlet passage therebetween, and a particle obstructing element centrally disposed in said nozzle.
